UNITED STATES PATENT OFFICE.

JOHN P. NIKONOW, OF BALTIMORE, MARYLAND.

MONKEY-WRENCH.

1,284,921.

Specification of Letters Patent. Patented Nov. 12, 1918.

Application filed November 1, 1917. Serial No. 199,639.

To all whom it may concern:

Be it known that I, JOHN P. NIKONOW, a citizen of Russia, and a resident of the city of Baltimore and State of Maryland, have invented a new and useful Improvement in Monkey-Wrenches, of which the following is a specification.

My invention relates to monkey wrenches and has particular reference to such mechanisms, as employ adjustable jaws with clamping faces, used in pipe wrenches.

The object of my invention is to provide a mechanism of the character, above indicated, which is simple and efficient in operation, which provides for an easy and positive adjusting means for its jaws, and which embodies a pivoted handle, acting as a lever on the moving jaw and causing a certain clamping effect between jaws to enable my wrench to be used on round objects, such as pipes.

In the construction of monkey wrenches difficulties have been encountered in making them sufficiently light, strong and cheap to manufacture and at the same time to have a provision for positive clamping of the work between the jaws, such as is required for pipe wrenches.

According to my invention, I employ a pivoted handle, acting as a lever on a movable jaw or on the adjusting means for same, and thereby I secure the desired clamping between the jaws.

In the accompanying drawings, Figure 1 represents an elevation of my mechanism; Fig. 2, side view; Fig. 3, longitudinal section of a modification; Fig. 4, section through 1-1 (on Fig. 1); Fig. 5, section through 2-2 (on Fig. 3); Fig. 6 shows more clearly working clearance for the screw head in the shell.

The stationary jaw 1 is riveted or otherwise fastened in a body portion or shell 2, which consists of two steel plates, riveted together as shown in Figs. 1, 2 and 4, or a plate bent over, as on Figs. 3 and 5. A movable jaw 3 slides inside of this shell. Thread grooves 4 are cut on the edge of this jaw to correspond with the thread of the actuating screw 5. Shell 2 is made large enough to fit jaw 3 and screw 5. A screw head 6 is provided on the screw for the purpose of turning this screw. This screw head 6 fits into an opening in the shell 2, so that screw 5 cannot move along its axis except within small limits, as it will be herein-

after explained. Therefore, with the turning of screw 5 to the right or to the left, the jaw 3 will slide accordingly in or out. A handle 7 is pivoted by means of a bolt or rivet 8 to the shell, and has an extension 9, which rests against screw head 6, partially (as shown on Fig. 3) or fully (as per Fig. 1) inclosing this screw head, thereby forming a pivotal connection between the handle and the screw. With this arrangement, my mechanism represents an ordinary monkey wrench, but in order to obtain clamping effect between the jaws, I provide the opening 10 in the shell sufficiently longer, than the axial length of screw head 6, so that the whole screw can move back and forth in the shell by the length of this clearance or difference between the length of opening and screw-head.

Therefore if the jaws are opened enough to go over a pipe, the action of the handle 7, when an effort is made to turn the pipe, will cause the screw 5 and the jaw 3 with it to move toward stationary jaw, thus causing clamping effect on the pipe, and this clamping will be in direct proportion with the force applied to the handle 7.

This clamping movement is limited by the amount of clearance, so that with $\frac{1}{16}$ " clearance (or lost motion), for instance, the jaws will move together not over $\frac{1}{16}$ ", so that my wrench, when properly constructed, while efficiently clamping pipes, cannot damage them or cause them to collapse.

Fig. 3 shows a modification, in which the pivot 8 is located between the screw and the stationary jaw, so that there is a slot 11 made for it in the movable jaw 3.

An important advantage of the mechanism above described is, that it is light, strong and easy to manufacture, as it can be made of thin stampings, combining the properties of a light and thin ordinary wrench with those of a pipe wrench.

Having thus described my invention, what I claim is:

1. In a wrench, the combination with a stationary jaw, a movable jaw, movable adjusting means in co-operation with said movable jaw, enlargement on said adjusting means, adapted to be actuated by the operator's fingers, a body portion, consisting of two pieces, attached on both sides to said stationary jaw and joined together on the other end, forming a space in the middle for said movable jaw and said adjusting

means, an opening in said body portion, adapted to fit said enlargement on said adjusting means, and a lever, pivoted to said body portion and having means to engage 5 the enlargement of the adjusting means to slide the adjusting means and the movable jaw.

2. In a wrench, the combination with a stationary jaw, a movable jaw, movable adjusting means in coöperation with said movable jaw, enlargement on said adjusting means, a body portion, consisting of two pieces, attached on both sides to said stationary jaw and joined together on the 10 other end, forming a space in the middle for said movable jaw and said adjusting means, and a lever, pivoted to the halves of the body portion, where they are joined together and having means to engage the enlargement of the adjusting means to slide the adjusting means and the movable jaw.

3. In a wrench, the combination with a stationary jaw, a movable jaw, movable adjusting means in coöperation with said movable jaw, said adjusting means consisting of a screw, an operating enlargement on said screw, a body portion consisting of two halves, attached on both sides to said stationary jaw and joined together on the 25 other end, forming a space in the middle for said movable jaw and said screw, openings in said body portion for said enlargement of said screw, and a lever formed of two halves, pivoted on both sides to said body portion, the halves of said lever having openings for said enlargement of 30

35

said screw, so as to render said enlargement accessible from the outside for the purpose of rotating said screw and having means to engage the enlargement of the adjusting means to slide the adjusting means and the movable jaw.

4. In a wrench, the combination with a stationary jaw, a movable jaw, having notches on its edge, movable adjusting means in coöperation with the notches of said movable jaw, a round operating enlargement on said adjusting means, a body portion, consisting of two halves, attached on both sides to said stationary jaw and joined together on the other end forming a space in the middle for said movable jaw and said adjusting means, openings in said stampings for said enlargement of said adjusting means, and a lever, formed of two halves, pivoted on both sides to said body portion, and extending over the enlargement of said adjusting means, the halves of said lever having openings, fitting over said enlargement of said adjusting means and enabling thereby rotation of said enlargement by the operator's hand, said lever also operating to actuate the movable jaw by engagement with the actuating means.

In testimony whereof, I have hereunto 65 subscribed my name this thirtieth day of October 1917.

JOHN P. NIKONOW.
